TRAVELING WAVE TUBES

Wellesley J. Dodds, Allentown, N. J., assignor to Radio Corporation of America, a corporation of Delaware

Application October 1, 1951, Serial No. 249,198

10 Claims. (Cl. 315—3.6)

This invention relates to electronic tubes, and particularly to tubes of the traveling or growing wave type.

In the usual traveling wave tube, an elongated helical electrode is disposed with its axis coincident with a rectilinear electron beam extending from an electron gun to a collector electrode. With such construction, the gain or amplification of the tube is a function of the length of the helical electrode and, consequently, a high gain tube is physically long. Also, because of the constructional difficulties, such tubes often require a high accelerating potential to obtain the necessary initial linear velocity of the electrons.

In accordance with the present invention, which affords high gain without need of excessively high accelerating voltage or excessive length of tube, the usual rectilinear electron beam is replaced by a substantially axially moving, non-rotating, helical electron beam. In the interaction region, the helical beam sweeps over or passes through a helical electrode structure whose axis substantially coincides with that of the helical beam and is of suitably different pitch for the desired interaction between the beam and the helical electrode structure.

More particularly, in accordance with the invention, the electrons from the gun are first subjected simultaneously to an alternating electric field and an axial magnetic field of such strength as to produce a revolving-pencil type beam and, upon entrance to a second zone, are subjected to a magnetic field of much greater strength which causes further movement of the beam as a helix having motion substantially of translation only toward the collector electrode.

In one form of the invention, the electrode structure swept by the helical beam comprises a two-conductor transmission line of helical form and whose pitch is different from the pitch of the beam so that there will be favorable interaction between the beam and the circuit constituted by the line.

The invention further resides in methods and arrangements having features of novelty hereinafter described and claimed.

For a more detailed understanding of the invention and for illustration of embodiments thereof, reference is made to the accompanying drawings in which:

Fig. 1 schematically illustrates the new type of traveling wave tube and its method of operation;

Fig. 2 is an axial sectional view of one form of the new traveling wave tube and its circuit connections; and

Fig. 3 is an axial sectional view of a modification of the two-conductor helical output structure of Fig. 2.

In accordance with the present invention, an axial constant magnetic field is combined with a transverse alternating electrical field in a first region to produce a revolving-pencil beam of spirally-traveling electrons. Then the electrons move into a second region having an axial magnetic field of much greater strength. The strong magnetic field constrains the electrons to motion in helical paths parallel to the magnetic field of such small radii that for

practical purposes the path of each electron may be considered straight. Since the electrons of the rotating beam successively enter the second regions at all points around a circle the result is a helical beam having substantially translational motion parallel to the axis.

Referring to Fig. 1, the electron gun 10 of the tube may comprise a cathode 11, a heater 12 therefor, and an accelerating and focusing electrode structure generically exemplified by electrode 13. In the absence of application of the fields subsequently discussed, the beam of electrons produced by gun 10 would travel in a rectilinear path to a collector electrode 14, forming a straight line beam indicated by a dot-dash line S, Fig. 2. Such straight line beam is utilized in prior types of traveling wave tubes and often requires, for high gain, the application of high accelerating voltage to the electrodes 13 and 14, or equivalent, and also requires a tube which is physically long.

In the new type of traveling or growing wave tube, the electrons from gun 10 are subjected simultaneously in zone #1 to an alternating electric field E_0 transverse to axis S and to a static, coaxial magnetic field H_1 . These two fields cause electron beam R to revolve about axis S in zone #1, generating a cone C whose apex is directed toward the gun 10 and whose base B is presented toward the collector electrode 14. More precisely explained, as the electric field E_0 deflects the electrons entering zone #1, they begin to move across the axial magnetic field H_1 . This motion transverse to the magnetic field causes the electrons to be deflected at right angles to the radial motion. The magnetic field strength H_1 is so chosen or adjusted that

$$\frac{H_1 e}{m}$$

is equal to $2\pi f_0$, where e and m are the charge and mass, respectively, of the electron, and f_0 is the frequency of the electric field E_0 . Under these conditions all the electrons tend to move in circular paths with the same angular velocity and in phase with the electric field. Hence, the electrons are continuously accelerated radially, moving in spiral paths of increasing radii. At any instant, all the electrons lie on a straight line, which revolves about the axis S to generate the cone C. The fields for effecting such revolution of the beam are produced by application of a signal voltage of frequency f_0 to the deflection plates 15, 15 disposed within zone #1 on opposite sides of the axis S, simultaneously with application of an axial magnetic field H_1 by any suitable means. For a more complete discussion of such arrangement, per se, reference may be had to Patent No. 2,542,797, issued February 20, 1951, to C. L. Cuccia.

As the beam passes from zone #1 into zone #2, it is subjected to a second coaxial magnetic field H_2 of field strength much greater than that of field H_1 in zone #1. In this second zone, the electron beam assumes the form of a helical beam T of diameter corresponding with the base of cone C. This helical electron beam does not rotate but has motion substantially of translation only toward the collector electrode 14. As each electron of beam R, traveling in a spiral path in zone #1, enters zone #2, it is constrained by the strong magnetic field to traverse a helical path parallel to the magnetic field of much smaller radius r , determined by the relation

$$r = \frac{mv}{H_2 e}$$

where v is the tangential velocity entering zone #2, and H_2 is the strong magnetic field strength in zone #2. This radius r can be made so small that the helical path may be considered as substantially a straight line.

In its passage through zone #2, the helical beam sweeps across a helical conductive structure, shown in Fig. 1, for example, as a two-conductor helical transmission line 16. The relative pitch of the axially moving helical beam may be so chosen that the points X, where the beam at some instant is sweeping the space between the conductors of the line 16, are one wavelength apart on the line. Under such circumstance, there will be induced in the coiled transmission line voltages which are of equal amplitude and like phase at points one wavelength apart along the line. The axial motion of the helical beam with respect to the stationary coiled transmission line causes the points X progressively to slide along the helical output structure at a rate determined by the pitch of the output helix 16, the pitch of the helical beam and the velocity of translation of the beam along the axis S. These parameters may be adjusted so that the velocity of points X along the convolutions of the transmission line 16 with respect to the characteristic velocity of a wave moving down the line produces maximum signal output.

It can be shown that if the helical beam and the line 16 have the same helix sense, the points X will move forward, in the same direction as the beam, if the beam pitch is less than the line pitch. This condition is shown in Fig. 1, where, for the sake of clarity of illustration only, the beam T is shown as having a pitch one-half of the pitch of the line 16.

If the beam and the line have opposite helix sense, the points X will move forward whether the beam pitch is greater or less than the line pitch. It will be understood that the helix sense of the helical beam can be reversed merely by reversing the direction of the axial magnetic field. When the beam and line have the same helix sense the speed of movement of the points X increases as the beam and line pitches are made more nearly equal. Therefore, the axial velocity of the beam may be adjusted to produce any desired interaction speed between the beam and the line.

Because of the interaction between the beam and the signal wave on the transmission line, the spacing between the electrons does not remain fixed in zone #2. There is repeated alternate bunching and separation of the electrons, the bunching becoming more and more pronounced as the collector is approached with consequent increase or growth of the wave traveling along the transmission line. This amplification phenomenon, in itself, is substantially that which occurs in traveling-wave tubes having an electron beam flowing rectilinearly through, and in coupling relation with, a helix or other traveling-wave circuit.

One embodiment of a tube utilizing the aforesaid novel principles is shown in Fig. 2, in which elements corresponding with those of Fig. 1 are identified by the same reference characters.

The electrons in passing through zone #2 eventually give up a substantial part of their energy to the transmission wave on the transmission line. For collection of the electrons after passage through zone #2, the collector electrode 14 is suitably positively biased at a relatively low positive potential by a direct-current voltage source, exemplified by battery 17. For imparting to the electrons the required initial velocity, the accelerating electrode 13, or equivalent, is suitably positively biased as by direct-current voltage source, exemplified by battery 18. With such an arrangement, as compared with traveling wave tubes of prior type, this accelerating potential for a given pitch of the helix is much less. The means for producing the fields H_1 and H_2 in zones #1 and #2 may be coils 19A and 19B fitting over the envelope 20 of the tube, or alternatively, either may be a circular permanent magnet magnetized to produce a field extending parallel to the axis of the tube. The ends of the transmission line 16 are sealed through the envelope 20, as shown in Fig. 2, to provide input and output

terminals for connection to a signal source and output load, respectively.

In the above discussion, the effects on the beam due to the transition from the first magnetic field to the second magnetic field have been ignored. In a practical embodiment of the invention, this transition will necessarily introduce at least some components of magnetic field transverse to the axis of the tube. Such transverse components will cause a reduction in the axial component of beam velocity in zone #2 which must be taken into consideration in determining the pitch of the output transmission line 16.

In the form shown in Fig. 2, the helical output structure is a two-wire transmission line 16 formed of parallel wires suitably supported internally of the envelope of the tube. Alternatively, as shown in Fig. 3, the output structure may be a tubular metallic, non-magnetic member 21, designed either to fit within the envelope of the tube or to form part of it. In either case, the cylindrical member is internally grooved as indicated at 22 to provide the equivalent of the two-wire helical transmission line of Fig. 2.

It shall be understood that the invention is not limited to the specific embodiments illustrated and that other forms of traveling wave tubes in which the electron beam traverses the drift space as a helix are within the scope of the appended claims.

What is claimed is:

1. A traveling wave tube comprising an electron gun and a collector electrode spaced from each other and defining a beam path therebetween, field-producing means for subjecting the electron beam in its passage from said gun toward said collector electrode to electric and magnetic fields to produce a helical beam of electrons having substantially axial translational movement only, and helical conductive structure swept by said helical beam, said field-producing means comprising deflection plates on opposite sides of said beam path to which an alternating signal is applied, and in which the pitch of the beam is different from that of said helical conductive structure.
2. A traveling wave tube comprising an electron gun and a collector electrode spaced from each other and defining a beam path therebetween, field-producing means for subjecting the electron beam in its passage from said gun toward said collector electrode to electric and magnetic fields to produce a helical beam of electrons having substantially axial translational movement only, and helical conductive structure swept by said helical beam, said field-producing means comprising means for applying to the electron beam an alternating electric field and a constant magnetic field respectively transverse and parallel to said beam path in a first zone adjacent to said gun to effect revolution of the beam about said path in a conical path whose base is presented toward the collector electrode, and in which the field-producing means provides a magnetic field of much greater field strength parallel to said beam path in a subsequent zone for producing said helical beam.
3. A traveling wave tube as in claim 2 in which said helical conductive structure is a two-conductor transmission line coiled to form a helix coaxial with said helical beam.
4. A traveling wave tube as in claim 2 in which said helical conductive structure is of solid construction internally grooved to form a helix.
5. A traveling wave tube as in claim 2 in which said helical beam and said helical conductive structure have the same helix sense and different pitches.
6. A traveling wave tube as in claim 2 in which said helical beam and said helical conductive structure have opposite helix sense.
7. A traveling wave tube comprising an elongated helical conductive structure, and means for producing a helical beam of electrons having substantially translational movement only along the axis of said helical con-

ductive structure; said means including: means spaced from said structure for producing a revolving beam of electrons which traces a circular trace coaxial with said structure in a transverse plane located adjacent to one end thereof; and means for subjecting said revolving beam, in a region containing said structure, to an axial constant magnetic field of sufficient field strength to cause the individual electrons of said beam to follow paths in said zone which are substantially straight and parallel to said axis.

8. A traveling wave tube comprising an elongated helical conductive structure, and means for producing a helical beam of electrons having substantially translational movement only along the axis of said helical conductive structure; said means including: electron gun means, spaced axially from said structure, for projecting an electron beam toward said structure along an initial path parallel to said axis; means for subjecting said beam in a first zone adjacent to said gun means to a transverse alternating electric field and a first axial constant magnetic field of predetermined field strength, to cause the electrons of said beam to spiral about said axis; and means for subjecting said beam in a second zone, substantially contiguous to said first zone and containing said structure, to a second axial constant magnetic field of much greater field strength than said first magnetic field, to cause said spiralling electrons to move in said second zone along paths which are substantially straight and parallel to said axis.

9. A traveling wave tube as in claim 8, wherein said means for subjecting said beam to a transverse alterna-

10

5 ing electric field comprises a pair of deflection plates on opposite sides of the beam path between said electron gun means and said structure.

10. The combination of a traveling wave tube as in claim 9 with a source of alternating voltage of predetermined frequency, wherein the field strength of said first magnetic field is equal to said frequency multiplied by $2\pi m/e$, where m and e are the mass and charge, respectively, of an electron.
